UNITED STATES PATENT OFFICE.

DANIEL B. LE VAN, OF CALDWELL, IDAHO.

BARREL-TONGS.

SPECIFICATION forming part of Letters Patent No. 630,866, dated August 8, 1899.

Application filed December 29, 1898. Serial No. 700,602. (No model.)

To all whom it may concern:

Be it known that I, DANIEL B. LE VAN, a citizen of the United States, residing at Caldwell, in the county of Canyon and State of Idaho, have invented certain new and useful Improvements in Barrel-Tongs; and I do hereby declare the following to be a full, clear, and exact description of the invention, such as will enable others skilled in the art to 10 which it appertains to make and use the same.

My invention relates to barrel-tongs, the object being to provide an improved device of this class which can be manipulated with rapidity and ease in suspending, rolling, or 15 shipping barrels or kegs.

My object is, particularly, to provide improved engaging devices whereby attachment to the barrel is had at the chimes thereof and also novel means for locking the tongs.

Having the foregoing and other objects in view, the invention is embodied in barrel-tongs comprising certain improved features and combinations of parts described herein-after and set forth in the appended claims.

In the accompanying drawings, Figure 1 is a perspective view; Fig. 2, a detail of one of the rollers and its fastening, and Figs. 3 and 4 details of the locking mechanism.

The arms 1 and 2 of the tongs are of bar- 30 steel and pivoted together at 3. Their extremitiess are twisted out of the planes of their length into fingers 4 and 5, which are disposed at an angle to the arms and are substantially parallel to each other.

There are two rollers 6 and 7, of hard wood 35 or metal, which are journaled on pins or studs 8 and 9. These pins have heads 10, which are countersunk in the faces of the rollers, while their other ends are also headed and

40 loosely received in openings 11 in the fingers. This loose or swiveled connection as used with the rollers constitutes a valuable part of the present invention. The rollers are the means employed for attaching the tongs to 45 the barrel by engaging and running against the chimes of the same, and by reason of the loose connection they can assume various angles, so that no matter how large or how small

the barrel may be or what the position of the tongs relatively thereof a firm hold is obtainable.

There is a handle 12, preferably of wood, composed of two longitudinal halves, which are fastened together by bolts 13 and 14, leaving a slot 15 between them. The inner faces 55 of the halves have grooves 16. The short end of arm 1 is pivoted on bolt 14, while the short end of arm 2 slides in the slot 15 and is provided with a cross-stud 17, whose ends slide in the two grooves 16. This improved 60 connection permits free relative movement of the arms, but assists the locking-catch in securing them in fixed relation when necessary.

The numeral 18 represents a locking-catch which is pivoted to the short end of arm 2 65 and is pressed by a spring 19 into engagement with any notch of a series 20 provided on the handle.

When using the device, the locking-catch is released and the rollers applied to the ends 70 of the barrel. They are then pressed up against the ends or heads of the barrel as far as possible and the catch allowed to snap into a notch on the handle. The operator on grasping the handle, to handle the barrel, will 75 pull the edges of the rollers against the chimes of the barrel, and the latter can then be pulled about, suspended, or handled as desired with the greatest ease, the rollers meanwhile running against the chimes. The loose connections of the rollers with the fingers is of great 80 advantage, because they permit the device to assume different positions without becoming disengaged from the barrel.

Having thus described my invention, what 85 I claim as new, and desire to secure by Letters Patent, is—

1. In a device of the class described, the combination with arms connected together for relative movement, of a member connected to one arm and having a slot and grooves, said other arm having its end movable in the slot and provided with a cross pin or stud 90 slidable in the grooves, and means for locking the said movable arm to the member at 95 different points.

2. In a device of the class described, the combination with arms pivoted together, of studs or pins loosely connected to the arms, rollers journaled on the studs or pins, a handle connected to one arm and having a slot and grooves and engaging devices, said other arm being slid able in the slot and having a cross-pin movable in the grooves, and a catch

for locking the said movable arm to the handle: 10

In testimony whereof I affix my signature in presence of two witnesses.

DANIEL B. LE VAN.
